UNITED STATES PATENT OFFICE.

PAUL F. COX, OF CHICAGO, ILLINOIS.

VENTILATOR.

1,263,382.

Specification of Letters Patent. Patented Apr. 23, 1918.

Application filed February 23, 1917. Serial No. 150,467.

To all whom it may concern:

Be it known that I, PAUL F. Cox, a citizen of the United States, and a resident of Chicago, in the county of Cook and State of Illinois, have invented certain new and useful Improvements in Ventilators, of which the following is a specification, reference being had to the accompanying drawings.

My invention relates to ventilators of a type especially designed for use in the window of a sleeping car, and it has for its principal object the provision of a form of device which shall be capable of being carried in an ordinary traveling-bag or suit-case, which shall have a neat appearance when out of use in condition for packing, and which shall be effective for admitting and controlling the desired amount of air. It is one of the specific objects of my invention to provide in a device of this type for readily and easily closing the opening through which the air is admitted, either partially or wholly as may be desired, without the necessity for removing the device from the window or for varying the position of the sash in any way. It is another object of my invention to provide suitable screens for preventing the admission of dirt and dust, and to provide suitable means for deflecting the air upward at its point of admission. It is another object to provide a device of this type of telescopic form capable of being extended for use in either direction whereby the air may be admitted at either side of the window as may be desired at either side of the car. It is still another object of my invention to improve devices of this type in sundry details hereinafter pointed out. The preferred means by which I have accomplished my several objects are illustrated in the drawings and are hereinafter specifically described. That which I believe to be new and desire to cover by this application is set forth in the claims.

In the drawings:

Figure 1 is a view showing a lower berth made up, with one of my improved ventilators in position in the window at the extreme foot-end of the berth;

Fig. 2 is a view similar to Fig. 1, but showing the berth at the opposite side of the car, and showing one of my improved ventilators in position at the foot, the telescopic ventilator being extended in the opposite direction from that shown in Fig. 1;

Fig. 3 is a perspective view of my im-

proved ventilator when out of use in condition for transportation;

Fig. 4 is a vertical cross-section taken substantially on line 4—4 of Fig. 7, showing the ventilator in position in a window;

Fig. 5 is a view of my improved device as seen from outside the car, the case being broken away in order better to show the construction, the view being taken substantially on line 5—5 of Fig. 4;

Fig. 6 is a vertical section taken substantially on line 6—6 of Fig. 4;

Fig. 7 is a view of my ventilator as seen from the right in Fig. 4 from the inside of the car, the casing being broken away;

Fig. 8 is a vertical section through the ventilator with the casing removed and with the device completely folded up ready for insertion in the casing;

Fig. 9 is a fragmentary view showing the construction of the frame of the ventilator whereby the desired slots are provided; in the completed frame, the upper portion is grooved as indicated in Fig. 8;

Fig. 10 is a section taken on line 10—10 of Fig. 4, showing the manner of connection of the deflector plate with the side members of the deflector as hereinafter described;

Fig. 11 is a view of the spring pin by which the frame is held in the desired position relative to the casing; and

Fig. 12 is a view similar to Fig. 8, but showing a modified form of structure.

Referring to Figs. 1 to 11, in which corresponding parts are indicated by the same reference characters,—15 indicates the casing which forms the outer telescopic member of my improved device, the casing being preferably formed of tin or aluminum. The other member which is adapted to fit snugly within the casing 15 is in the form of a frame comprising ends 16—17 and side bars 18—19. As is best shown in Figs. 3 and 9, the end pieces 16 and 17 are formed in three separate pieces so as to provide slots 20—21, the side bars 18 and 19 being grooved, as is clearly shown in Fig. 8, such grooves being in registration with the slots 20—21. A screen 22, preferably formed of a fine wire netting, is slid into position in the slot 20 of the frame, being of sufficient size to cover the frame completely from end to end. A slide 23 is slidably mounted in the slot 21, being also of a size to fill the frame completely from end to end.

A deflector plate 24 is swingingly mount-

ed in position upon the frame by having its lower edge extended within a channel member 25 which is preferably formed of tin or other light metal. As is shown in Figs. 4 and 8, the side bar 19 is beveled at one side so as to permit the deflector plate 24 to swing outward from the position shown in Fig. 8 to the position shown in Fig. 4. The deflector plate 24 is preferably formed of metal plate bent at its ends to embrace the edges of suitable triangles 27 formed of cloth or other pliable material (see Fig. 10). The rear edges of the triangles 27 are secured to the end bars of the frame by means of tacks or in any other suitable manner. A curtain 28 formed of cloth or any other suitable pliable material is connected at its upper edge to the bar 18 of the frame, being adapted to hang straight downward between the deflector plate 24 and the slide 23 as shown in Fig. 8, or to extend outward over the edge of the deflector plate 24 when such plate is swung into the position shown in Fig. 4. The curtain 28 is provided at its lower edge with a bar 29 of any suitable type adapted to be of sufficient weight for holding the curtain 28 nicely in position. The channel 25 is preferably provided with slots 30 for the escape of dirt and dust as hereinafter described. The upper edge of the curtain 28 in the construction shown is secured in position by means of a channelled member 31 which embraces the bar 18. The channel member 31 is provided with a groove in its web portion for the reception of a strip of felt 32.

When the frame with the several parts carried thereby as above described is in position within the casing 15 as shown in Fig. 3, it is adapted to be secured in position therein by means of a pin 33 extending through a hole 34 (see Fig. 3) at one end of the casing and a registering hole 35 in the corresponding end of the frame. It is evident, however, that even without the use of the pin 33 the friction of the strip 32, which is then compressed, against the upper wall of the casing 15, will tend to hold such frame in place within the casing. Whenever it is desired to insert the ventilator in a window, the pin 33 is removed and the frame is drawn from either end of the casing as may be desired, depending upon whether the casing is to be placed at the side of the window which is in advance or at the rear in the movement of the train. When the sash of the window, such as that indicated by 36 in Fig. 4, is raised sufficiently, the frame is drawn out from the casing so as to bring the end of the frame of the ventilator against one side of the frame of the window while the end of the casing is against the opposite side of the frame of the window, the pin 33 being then

inserted through registering openings 34 and 35 so as to hold the ventilator against withdrawal, the sash being then lowered into contact with the casing 15 and the strip of felt 32 which expands sufficiently to provide a close fit. The deflector plate 24 is then drawn out into the position shown in Fig. 4, and the curtain 28 is lifted out of the way so as to permit the desired adjustment of the slide 23. By means of grooves or notches 37, or any other suitable means upon the slide 23, the slide is moved into position to leave just as great an opening for the admission of air as may be desired. The curtain 28 is then extended outward over the upper edge of the deflector plate 24 as shown in Fig. 4. As will be readily understood, if it is desired at any time to vary the amount of air being admitted, this can be accomplished by merely raising the curtain 28 and moving the slide 23 as may be desired. A further control of the amount of air being admitted to the berth is provided through the adjustment of the deflector plate 24. In the construction shown, no means is provided for holding the deflector plate in different adjusted positions other than by the contact of the curtain 28 upon the plate.

By the use of the double screen construction such as is provided by the screen 22 directly within the opening below the sash and the second screen comprising the triangular pieces 27 and the curtain 28, the force of the air is broken and the dirt and dust carried by the air are prevented from entering the berth. When the ventilator is being taken from the window, such dirt and dust as may have gathered between the deflector plate 24 and the screen 22 is adapted to pass downward for escape through the slots 30 in the channel member 25.

In the construction shown in Fig. 12, a frame 38 is employed similar in a general way to the frame above described provided with slots and grooves for the insertion of a screen 39 and a slide 40. A piece of rubber tubing 41 secured upon the upper edge of the frame takes the place of the strip of felt 32 of the construction first described. The frame 38 is to be contained in a casing such as the casing 15 above described. The form of device shown in Fig. 12 is capable of being produced very cheaply and is a form having considerable merit as a ventilator, even though not involving all of the advantages of the construction first described. It is believed that the operation of the device of Fig. 12 will be readily understood without a further description.

What I claim as my invention and desire to secure by Letters Patent, is—

1. In a ventilator for closing the space between the frame and the edge of the sash in a partially open window, the combina-

- tion of a casing adapted to close one side of said space, a frame slidably mounted in said casing and adapted to be extended from the casing to the opposite side of said space, 5 a screen covering the opening in said frame, and an expansible member secured along the upper edge of said frame adapted to expand to fill the space between the edge of the frame and the edge of the sash while 10 at the same time being capable of being drawn into said casing.
2. In a ventilator for closing the space between the frame and the edge of the sash in a partially open window, the combination 15 of a casing adapted to close one side of said space, a screen slidably mounted in said casing and adapted to be extended from the casing to cover the remainder of said space, and a deflector plate movable slidably with said screen out of said casing and also adapted to swing on a horizontal axis relative to said screen for directing the air upward at the point of admission, said deflector plate being adapted when in closed 20 position to pass with the screen into said casing.
3. In a ventilator for closing the space between the frame and the edge of the sash in a partially open window, the combination 25 of a casing adapted to close one side of said space, a frame slidably mounted in said casing and adapted to be extended from the casing to the opposite side of said space, a screen covering the opening in said frame, and a deflector plate swingingly mounted on a horizontal axis on said frame opposite the space covered by said screen for directing the air upward at the point of admission, said deflector plate being adapted to 30 pass with the screen into said casing.
4. A ventilator for closing the space between the frame and the edge of the sash in a partially open window, comprising in 35 combination a screen covering a portion of said space, means slidably mounted relative to said screen for closing the remainder of said space, a deflector plate swingingly mounted on a horizontal axis on said screen member adapted to direct the air upward at the point of admission, means for screening the space between said first-named screen and the side edges of said deflector plate, and a curtain secured to the upper portion of said screen member and adapted to extend either downward inside of the deflector plate or outward over the upper edge of said deflector plate. 50
5. In a ventilator for closing the space between the frame and the edge of the sash in a partially open window, the combination 55 of a casing adapted to close one side of said space, a frame slidably mounted in said casing and adapted to be extended from the casing to the opposite side of said space, a screen covering the opening in said frame, a deflector plate swingingly mounted on a horizontal axis on said frame opposite the space covered by said screen for directing the air upward at the point of admission, pliable screening means connecting the ends of the frame with the ends of said extended deflector plate, and a curtain adapted to extend either downward inside of said deflector plate or over the upper edge of said plate. 60
6. In a ventilator for closing the space between the frame and the edge of the sash in a partially open window, the combination 65 of a casing adapted to close one side of said space, a screen frame slidably secured in said casing and adapted to be drawn out from one end thereof sufficiently to close the remaining portion of such opening, the lower bar of such frame being cut away at an angle along one face, a plate secured to said lower bar and having an upturned flange opposite said beveled face, and a deflector plate having its lower edge 70 within the space between the said flange and beveled face and adapted to swing outwardly for upwardly directing the air admitted through the screen. 75
